UNITED STATES PATENT OFFICE.

THOMAS ISHERWOOD AND WILLIAM NUTTALL, OF WESTERLY, RHODE ISLAND, ASSIGNORS TO THE NATIONAL FANCY WOOLEN LOOM-STOP-MOTION COMPANY, OF SAME PLACE.

IMPROVEMENT IN WEFT-STOP MECHANISMS FOR LOOMS.

Specification forming part of Letters Patent No. 154,254, dated August 18, 1874; application filed April 25, 1874.

To all whom it may concern:

Be it known that we, THOMAS ISHERWOOD and WILLIAM NUTTALL, of Westerly, in the county of Washington and State of Rhode Island, have invented a new and useful Improvement in Weft-Stop Mechanism for Looms, of which the following is a specification:

Our present invention relates to looms having one or more wires to be presented to the weft and comb it against the weft fork or latch to insure the proper action when the weft is present, and so prevent the shipper from being thrown off; and it consists of a new arrangement of devices for causing the tripping of the shipper-lever when the weft is not present, by which we are enabled to dispense with an apparatus arranged in front of the cloth-roll, and it is also simpler and cheaper than the apparatus commonly used.

Figure 1 is a front elevation of a loom having our improved stop-motion applied to it, a part of the front beam being broken out to show the apparatus clearly. Fig. 2 is a side elevation of the loom with a part of the frame broken out.

Similar letters of reference indicate corresponding parts.

A represents the wire rising up through the lathe behind the weft B. T is the weft-fork in front of the weft. This wire A we mount on a rising-and-falling piece, D, below the race-beam E, by pivoting it thereto at F, so as to swing forward and backward, and on the pivot or on the wire itself we arrange a tripping-finger, G, which is to be swung forward when the weft is present by the backward pressure of the weft-fork and weft on the wire A, to be held in the position for allowing the shipper to remain undisturbed; but when the weft fails to be present, to press the wire back, a light spring, H, which is suitably arranged for the purpose, holds the finger G back over the horizontal arm I of an elbow-lever, which has a rod, J, projecting from the side of its vertical arm K, so that when the block D goes down the finger will swing the rod forward, and hold it in the position to strike the lever

L, when the lathe beats up and causes it to throw off the shipper-lever M. The elbow-lever I K is pivoted to a bracket, N, projecting downward from the race-beam; but the block D, on which the wire is mounted, is attached to the upper end of the connecting-rod O, and works in guides P in the bracket, and the connecting-rod is attached to the lever Q, which is forced downward by the cam R and raised by the spring S. The cam throws the lever down during the latter part of the beat up, and if the weft is present and presses the wire back properly the finger G goes down in front of arm I and does not disturb it. The weft-fork T we suspend from the upper part of the loom-frame by an arm, U, so as to leave the front of the cloth-roll free, and we mount it on a pivot, V, so that it can be thrown over back out of the way, as indicated in dotted lines W, when it may be required to do so. A light spring, X, holds the arm and the fork to cause the latter to press the wire A back by the weft.

It will be seen that in this arrangement the wire A acts as a tripper for freeing the shipper-lever, while the weft-fork T takes the office of a comb for pressing the weft against the tripper.

If the feelers be arranged in front of the lathe, it will often be found that they will rise up in front of the weft and throw off the belt when the weft is all right, owing to their position so far forward. We find that the nearer we can get the feelers to the reed, and yet have them work unobstructedly, the better, and, in practice, we arrange them about half an inch in advance of it.

By arranging the feelers to rise up through the lathe they may come up near the weft, and thus have room to be swung back by the weft, when it is present, for moving the tripping-finger out of the way of the throwing-off lever, whereas if arranged on the front of the lathe, or in advance of it, it is necessary for them to be at the extreme of the backward range when they rise up to insure their coming behind the weft, and then, in order to move for throwing the tripping-finger, so as

to act on the throwing-off lever, in case of the absence of the weft, they must swing forward, for which there is not space between the line where the weft is left by the shuttle and the reed, nor time between the rising of the fingers and the then forward movement toward the weft.

Having thus described our invention, we claim as new and desire to secure by Letters Patent—

1. The wire A, pivoted to a rising-and-falling support, D, and provided with the finger G, and spring H, and the elbow-lever I K, and rod J combined with the lathe, the lever L and the feeding-fork T suspended from the loom-frame, all operating together substantially as specified.

2. The vertically-reciprocating wire H, the support D, the tripping-finger G, guide P, rod O, spring S, lever Q, and cam R, in combination with the lathe, all arranged and constructed to operate substantially as herein described.

3. The fork T, suspended from the upper part of the loom-frame, in combination with the vertically-reciprocating wire A, substantially as specified.

THOMAS ISHERWOOD.
WILLIAM NUTTALL.
